UNITED STATES PATENT OFFICE

WHEELER H. VIBBER, OF NEW LONDON, CONNECTICUT

ELECTRIC CONDUIT BUSHING

Application filed June 19, 1928. Serial No. 286,505.

This invention relates to an improvement in so-called conduit-bushings or terminals which are adapted to be secured to the ends of electric conduits for the double purpose of providing a smooth non-abrading terminal through which the circuit-wires may pass and also providing means whereby the conduit may be electrically grounded.

I am aware that many fittings have been devised for the purpose above mentioned but they have all been more or less awkward to use, owing to the difficulty of attaching grounding-connections thereto after they have been installed in situations where space is limited.

The object of this invention is to produce a simple and effective conduit-bushing or terminal requiring a minimum radius of swing and provided with conveniently positioned means readily accessible in cramped quarters for attaching ground-connections.

With this object in view my invention consists in a conduit-bushing characterized by a ring-portion adapted to be secured to the end of an electric conduit and a lug upstanding from the outer face of the said ring-portion and provided with a screw-receiving bore having its axis disposed transverse to the axis of the said ring-portion.

30 In the accompanying drawings:

Fig. 1 is a view in front elevation of a junction-box having two conduit-bushings constructed in accordance with my invention, installed therein;

35 Fig. 2 is an enlarged-scale top or plan view of my improved conduit-bushing;

Fig. 3 is a view thereof in elevation;

Fig. 4 is a similar view but viewing the bushing at a right angle from the position in 40 which it is shown in Fig. 3;

Fig. 5 is a transverse sectional view on the line 5—5 of Fig. 2; and

Fig. 6 is a view corresponding to Fig. 5 but showing a modified form of grounding-lug.

45 In carrying out my invention as herein

shown my improved conduit-bushing comprises a ring-portion 10 formed with an internally-threaded axial bore 11 for the reception of the threaded outer end 12 of an electric conduit 13, the extreme outer end of which latter is adapted to abut against the inner face 14 of an annular stop-flange 15 overhanging the threaded bore 11 aforesaid and having its outer portion rounded as at 16 to provide a non-abrading surface against which the circuit-wires may rest.

Upstanding from the outer face of the ring-portion 10 of my improved bushing is a grounding-lug 17 having parallel faces 18 and 19 formed transversely with an internally-threaded screw-receiving bore 20 adapted to receive a binding-screw 21. The periphery of the ring-member 10 is provided as shown with a number of vertical ribs 22 by means of which the bushing may be turned 65 home upon the conduit 13.

In Fig. 1 of the drawings I have shown a junction-box 23 through the opposite walls of which project two conduits 13, the ends of both of which are provided with my improved conduit-bushings. As is the usual practice, each of the said conduits has threaded upon it a binding-nut 24 engaging the outer face of the junction-box so as to bind the bushings against the inner wall thereof.

By reference to Fig. 1 of the drawings, it will be seen that by providing the upstanding grounding-lugs 17 equipped with binding-screws extending transverse to the axis of the ring-portion of the respective bushing, the installation of a grounding-wire 25 extending between the respective conduit-bushings in accordance with the requirements of numerous electrical codes, is greatly facilitated, since it is a relatively simple 80 matter to reach in laterally through the open face of the junction-box 23, with a screwdriver or other tool and firmly bind the screws 21 upon the grounding-wire.

Heretofore it has been the general prac- 90

tice to provide the ring-members with radially-extending grounding-lugs through which binding-screws extend in a direction parallel with the axis of the ring, so that not only is the diameter of the bushing increased but the binding-screw is located in a position which renders it very inaccessible to a screw-driver or other tool, since the cramped quarters such for instance as the interior of the outlet-box 23 renders it impossible to employ a screw-driver in a vertical position as is required by the vertical position of the screw. Under such circumstances, therefore, it is necessary for the electrician virtually to "worry" home the binding-screw.

In Figs. 1 to 5 of the drawings I have shown the head of the binding-screw 21 overhanging the bore 11 in position to clamp the grounding-wire against the face 18 of the lug 17. Under certain conditions it may be desirable to reverse the screw so that it will bind the grounding-wire against the opposite face 19 of the said lug, which may be readily done.

In Fig. 6 of the drawings I have shown the lug 17 formed with an inclined inner face 26 and provided with a threaded screw-receiving bore extending at a right angle to it and, therefore, at a slight angle with reference to the plane of the ring. In this instance, however, like that shown in the preceding figures, the said bore, and the binding-screw which it receives, is disposed transverse to the axis of the bushing-structure and is, therefore, conveniently available for the application of a grounding-wire.

I claim:

1. A conduit-bushing comprising a ring-portion adapted to be secured to the end of a conduit; and a lug upstanding from the outer end face of the said ring-portion in a plane substantially parallel with the axis thereof and provided with a screw-receiving bore having its axis disposed transverse to the axis of the said ring-portion.

2. A conduit-bushing comprising a ring-portion adapted to be secured to the end of a conduit; and a lug upstanding from the outer end face of the said ring-portion in a plane substantially parallel with the axis thereof and provided with an internally-threaded screw-receiving bore having its axis disposed transverse to the axis of the said ring-portion.

3. A conduit-bushing comprising a ring-portion adapted to be secured to the end of a conduit; and a grounding-lug upstanding from the outer end face of the said ring-portion in a plane substantially parallel with the axis thereof and having substantially parallel opposite faces and provided with a screw-receiving bore intersecting both of the said parallel faces and having its axis disposed transverse to the axis of the said ring-portion.

4. A conduit-bushing comprising a ring-portion adapted to be secured to the end of a conduit; and a lug upstanding from the outer end face of the said ring-portion in a plane substantially parallel with the axis thereof and provided with a screw-receiving bore having its axis disposed at a substantial right angle with respect to the axis of the said ring-portion.

In testimony whereof, I have signed this specification.

WHEELER H. VIBBER.
